UNITED STATES PATENT OFFICE.

JOSEPH L. ANDERSON, OF TEXAS, MARYLAND.

HEATER AND MUFFLER.

1,173,403.

Specification of Letters Patent. Patented Feb. 29, 1916.

Application filed November 13, 1914. Serial No. 871,941.

To all whom it may concern:

Be it known that I, JOSEPH L. ANDERSON, a citizen of the United States, residing at Texas, county of Baltimore, and State of Maryland, have invented certain new and useful Improvements in Heaters and Mufflers, of which the following is a specification.

This invention relates to automobile heaters.

My object is to provide an improved heater for automobiles, particularly one adapted for use as a foot-warmer, which will utilize the exhaust gases from the motor without creating material back pressure and will also serve as a muffler.

My invention embodies an improved construction and combination of parts enabling the heat of the exhaust gases to be distributed, by radiation, under the control of the occupants of the automobile, so that a greater or lesser degree of heat may be obtained without any of the gases being discharged into the automobile and without unnecessary or unusual noise in muffling the exhaust.

My invention is adapted for easy and convenient access to its interior so that inspection or cleaning may be had without difficulty and the construction is such that the heater and muffler may be manufactured at low cost.

The invention is set forth fully herein-after and the novel features are recited in the appended claims.

In the accompanying drawings: Figure 1 is a perspective of a portion of an automobile showing the position the heater and muffler occupy; Fig. 2, a longitudinal section of the heater and muffler; Fig. 3, a section on line 3—3, Fig. 2; Fig. 4, a section on line 4—4, Fig. 2; and Fig. 5, a detail showing how the parts may be made of sheet metal.

My combined heater and muffler is adapted to be set in an opening cut in the floor of the car, as shown in Fig. 1, the body of the heater depending below the floor and the top plate of the heater and muffler resting on the floor and covering the opening. The heater is thus positioned properly for use as a foot-warmer and presents practically no obstruction on the floor of the car. It is also arranged so that it is in the general usual position occupied by a muffler. At those seasons of the year when a heater

is not needed, the heater may be taken out and stored and the flooring re-inserted where cut out and the usual muffler attached to the exhaust pipe, but the device may remain on the car at all times as I have provided a register as an improvement, whereby the radiation of heat may be controlled.

The heater may be wholly constructed of cast plates and a cast shell, as shown in Figs. 2, 3 and 4, or it may be made of sheet metal, as indicated in Fig. 5, and I lay claim to both forms of slidably supporting the partitions, to-wit: by grooves cut or formed in the walls of the shell or grooves defined by lips or flanges on the walls of the shell.

Referring first to Figs. 2, 3 and 4, the ends 1 and bottom 2 are cast as a single piece. The ends 1 have inwardly projecting flanges or a plurality of ears 3. The top plate 4 is secured to the ears 3 in any suitable manner, either permanently or detachably. The sides 5 overlap the ends 1 and underlie the overhanging side parts 6 of the top plate 4 and are secured by removable cross bolts 7. The sides and ends are provided with channels 8. Partitions 9 have their end and side edges received in the channels 8, the fit being a snug one and yet permitting the partitions 9 to be removed by sliding them in the channels 8 of the ends 1, when either or both of the sides 5 are removed. This construction does away with expensive castings and provides easily cleaned flat surfaces. The partitions 9 may be readily removed on disconnecting the bolts and the entire interior of the heater and muffler quickly and easily cleaned. The two lowermost partitions have slots or openings 10 at opposite ends, but the uppermost partition 9 is imperforate and constitutes the bottom of a heat chamber 11 to which the gases have no access. The heat in this chamber 11 is derived solely by radiation through the uppermost partition 9. The pipe coupling 12 is adapted to be connected to the exhaust discharge pipe of the motor of the automobile and hence the exhaust gases when at their greatest temperature, enter the chamber 13 and thence pass the full length thereof and dive down through opening 10 into chamber 14, thence passing in an opposite direction throughout the full length of chamber 14 and diving down the other opening 10 into the lowermost chamber 15, whence they are voided through the exhaust outlet 16, to the atmosphere. The greatest temperature

of the gases entering at 12 is, therefore, had to heat the chamber 11 and, as the exhaust gases pass into the chamber 14, they are subject to the heat of subsequent fresh exhaust gases entering chamber 13, and when finally passing into chamber 15, they receive the heating effect of the gases in the chamber 14. This return arrangement of the chambers is, therefore, availed of for the double purpose of obtaining a high heat radiation into chamber 11 and for muffling the sound of the exhaust.

The plate 4 is provided with openings or slots 17, as preferred, and below this plate 15 is a slidable damper plate 18 which has openings or slots 19 adapted to register with the openings 17 when the plate 18 is moved in a right-hand direction, Fig. 2. The sides 5 are provided with a plurality of lips or 20 a single flange 20 to support the damper plate 18. The plate 18 may be manipulated by any suitable device, such, for instance, as the finger-button 21.

Referring to Fig. 5, I have shown the end 25 1^a and the bottom 2^a as formed in a single piece from sheet metal. The remaining end 1^a will be integral with the bottom 2^a. The sides 5^a will be of sheet metal and held by bolts as previously explained. The channels 8^a on the ends 1^a and sides 5^a will be formed by lips, flanges or ears 22 secured, as for instance, by riveting.

An asbestos covering 23 is preferably provided on the ends 1, bottom 2 and sides 5 35 to minimize radiation except through the top of the heater. The inside faces of the bottom, sides and ends are preferably lined with a suitable non-corrosive metal to resist the corroding effect of the exhaust gases. 40 Perforations can be substituted for the slots in one or more of the partitions.

I am aware that other modifications may be resorted to in carrying out my invention within the spirit and scope thereof, and I 45 do not, therefore, limit myself to the details of construction shown, except where specified in the claims.

Having thus described my invention, what I claim as new and desire to secure by Letters Patent, is:—

1. A combined heater and muffler for automobiles comprising, as a unitary structure adapted to be bodily inserted in the floor of an automobile, a shell or casing having means in the lower portion for admitting and discharging exhaust gases and for causing them to travel in a circuitous path therein, and a heat distributing compartment in its upper portion whose walls are

attached to and self-contained with said shell or casing, said compartment being subject to the heating effect of the exhaust gases but out of communication therewith and having an outer wall or plate provided with openings, and a damper controlling 65 said openings, whereby said heat distributing compartment may be completely closed, or opened, at will, said compartment being otherwise closed.

2. In a combined heater and muffler for 70 automobiles, a shell or casing having removable walls, a plurality of removable partitions within said shell or casing and subdividing it into gas compartments and a heat distributing compartment, the partition intermediate the gas compartments having an opening which places said compartments in communication, the partition which defines the heat distributing compartment being imperforate, and an inlet and off- 80 take for the respective gas compartments.

3. In a combined heater and muffler for automobiles, a shell or casing having removable walls, a plurality of removable partitions within said shell or casing and subdividing it into gas compartments and a heat distributing compartment, the partition intermediate the gas compartments having an opening which places said compartments in communication, the partition which defines 90 the heat distributing compartment being imperforate, an outer wall or plate for said heat distributing compartment, and a damper for controlling said outer wall or plate.

4. In a combined heater and muffler for automobiles, a shell or casing having separable walls provided with channels, partitions slidably received in said channels and subdividing the shell or casing into compartments, said partitions having openings whereby the compartments are placed in communication, an inlet for the first compartment and an outlet for the final compartment, another removable partition similarly slidably seated, said partition being imperforate and serving as a wall of one of the compartments aforesaid, and a damper controlled outer wall or plate for the shell or casing which defines, in connection with the last-named partition, a heat distributing compartment.

In testimony whereof, I hereunto affix my signature in presence of two witnesses.

JOSEPH L. ANDERSON.
